UNITED STATES PATENT OFFICE.

BENJAMIN T. BABBITT, OF NEW YORK, N. Y.

IMPROVED ARMOR-PLATE FOR SHIPS AND OTHER BATTERIES.

Specification forming part of Letters Patent No. 37,380, dated January 13, 1863.

To all whom it may concern:

Be it known that I, BENJAMIN T. BABBITT, of the city, county, and State of New York, have invented a new and useful Improvement in the Construction of Iron Ships and Fortifications; and I do hereby declare that the following is a full, clear, and exact description of the same, reference being had to the accompanying drawings, forming part of this specification, in which—

Figure 1 is a transverse section of a vessel constructed according to my invention. Fig. 2 is an outside view of a portion of the side of a vessel constructed according to my invention. Fig. 3 is a vertical section corresponding and parallel with Fig. 2. Fig. 4 is a transverse section corresponding with Figs. 2 and 3, in a different plane from Fig. 1. Fig. 5 is a side view of one of the castings by which the parts of the wrought-iron framework of the vessel are united.

Similar letters of reference indicate corresponding parts in the several figures.

To enable others to construct vessels and fortifications according to my invention, I will proceed to describe it with reference to the drawings.

A A, B B, and C C are the series of wrought-iron bars, the first, A A, being arranged at suitable distances apart in substantially the same manner as the ribs of an ordinary vessel, the second, B B, arranged at suitable distances apart lengthwise of the vessel upon and in contact with the outer surfaces of A A, and the third, C C, arranged at suitable distances apart in the same direction as B B upon and in contact with the inner surfaces of A A. The several bars may be of various forms in their transverse sections; but I prefer to make the bars A A of square or parallelogrammic form, and the bars B B and C C of wedge form—that is to say, with two opposite sides oblique to each other, as shown in Figs. 1 and 4, the other two sides being parallel with each other—and when of such form I arrange the latter bars with the broadest of their two parallel sides in contact with the bars A A. By this means I form spaces of dovetail form between the bars B B and C C for the reception of the cast-iron, which is run in between them in the form shown at a a in Figs. 1, 2, and 4, and into the spaces between the bars A A, as shown at b b in Figs.

2 and 3, and thus made to secure the whole together in the most firm and solid manner by the contraction to which it is subject in cooling. The deck or roof of the vessel is composed of bars A' A', B' B', and C' C', united by cast iron in a similar manner, the bars A' A' corresponding in character with A A, and those B' B' and C' C' corresponding with B B and C C.

I propose to make the castings between the bars of as large size as is conveniently practicable. Those which are represented are each large enough to fill two of the spaces formed between the bars A to the depth of two bars B B C C and two of their intervening dovetail spaces, as shown at b b in Figs. 3 and 4, and to fill two of the spaces between the bars B B and two of the corresponding spaces between the bars C C to a length equal to the width of two bars A A and two intervening spaces, as shown at a a in Fig. 2; but, whatever the number of spaces which each casting fills, the portions b b of the several castings should meet each other opposite the centers of the bars B B and C C, as shown in Figs. 3 and 4, and the portions a a meet each other opposite the centers of the bars A A, as shown in Fig. 2. The form of the castings will be best understood by a comparison of Figs. 4 and 5, and their arrangement by a comparison of Figs. 3 and 4. The transverse section, Fig. 1, is taken close to the side of one of the bars A A, and Fig. 4 is taken midway between two of the said bars.

The molds to form the castings between the several bars are completed by means of blocks of metal temporarily inserted and secured between the several bars, and plates temporarily applied and secured to the exteriors of the bars B B and C C. The tops of the molds thus formed may be left open and the metal poured in till it comes to the required height. After some of the lower castings have been formed in their places, they form portions of the molds for casting the next ones above and at the sides of them.

In the construction of the vessel the bars B B and C C are only applied in their places as fast as the structure is proceeded with, as it would be useless to arrange them all in position, for the reason that they would be displaced by the shrinkage of the castings, and, besides, they would interfere with the pour-

ing of the metal. When the said bars have been applied in their places, they may be temporarily secured by means of clamps until the cast-iron has been poured between them and become solid. By this mode of constructing iron vessels, which is also applicable to the construction of fortifications or any defensive works, a structure of solid iron may be obtained, the several parts being perfectly united by the powerful agency of the shrinkage of the castings, the portions *a a* of which form dovetails and have their outward taper so formed by making the bars B B and C C of proper form that the shrinkage of the dovetails toward the bars A A rather more than

compensates for their shrinkage from the bars B B and C C, and so keeps them tight and causes them to draw B B and C C tightly against A A.

What I claim as my invention, and desire to secure by Letters Patent, is—

Having the bars B C made in wedge form, and combined, in the manner shown, with the bars A and the cast-metal filling, all as set forth.

B. T. BABBITT.
